UNITED STATES PATENT OFFICE.

PERRY S. BAUER, OF CHICAGO, ILLINOIS, ASSIGNOR TO BAUER TAXICAB MANUFACTURING CO., OF CHICAGO, ILLINOIS, A CORPORATION OF ILLINOIS.

DESIGN FOR A TAXICAB BODY.

Application filed May 23, 1924. Serial No. 9,693. Term of patent 14 years.

To all whom it may concern:

Be it known that I, PERRY S. BAUER, a citizen of the United States, residing at Chicago, in the county of Cook and State of Illinois, have invented a new, original, and ornamental Design for Taxicab Bodies, of which the following is a specification, reference being had to the accompanying drawing, forming a part thereof, in which—

Figure 1 is a perspective view, lined for black and red, showing my new design. Figure 2 is a diagrammatic horizontal longitudinal section.

I claim:

The ornamental design for a taxicab body, as shown and described.

PERRY S. BAUER.
